HOLDER FOR A GOLF BALL MARKER

Morris Kortick, Cranston, R.I., assignor to Troy, Inc.,
Providence, R.I., a corporation of Rhode Island

Filed Oct. 17, 1962, Ser. No. 72,147

Term of patent 3½ years

(Cl. D17—3)

FIG. 1

FIG. 2

FIG. 3

FIG. 4

FIG. 5

FIG. 1 is a front elevation of a holder for a golf ball marker showing my new design.

FIG. 2 is a bottom plan view thereof.

FIG. 3 is a side elevation thereof.

FIG. 4 is a top plan view thereof.

FIG. 5 is a rear elevation thereof.

The dominant features of my design reside in the portion shown in solid lines.

I claim:

The ornamental design for a holder for a golf ball marker, as shown and described.
